UNITED STATES PATENT OFFICE.

FRANK WHEELER PLANE, OF LONDON, ENGLAND.

RECEPTACLE FOR VARNISH, PAINT, AND THE LIKE.

1,396,053.

Specification of Letters Patent.

Patented Nov. 8, 1921.

Application filed January 27, 1919. Serial No. 273,217.

To all whom it may concern:

Be it known that I, FRANK WHEELER PLANE, a citizen of the United States, residing at London, England, have invented 5 new and useful Improvements in Receptacles for Varnish, Paint, and the like, of which the following is a specification.

This invention relates to receptacles for carrying liquid coverings such as varnish, 10 dope, paint and the like liquids which quickly solidify during the process of their application, and thus form a film on the surface of the liquid, such receptacles being of the known kind comprising, in combination, 15 a closed storage receptacle, and detachable brush bath, the brush bath being automatically replenished with liquid on the bird-fountain principle and having a flange facilitating the removal of surplus liquid from 20 the brush.

According to this invention, the closed storage receptacle has a sloping bottom to insure complete emptying of the liquid into the brush bath, and the storage receptacle 25 has permanently attached to it a screwed cap adapted to close the exit when the brush bath has been removed; the said brush bath being provided with internally depending drip flanges formed around it.

30 A typical construction of the combined storage receptacle and brush bath according to this invention is shown in the accompanying drawing, Figure 1 being a vertical section and Fig. 2 a plan on which the storage receptacle is numbered 1, the stopper at top 2, the outlet at bottom 3, the brush bath 4. A sloping bottom or diaphragm 5 is provided to insure the entire contents 9 of the storage receptacle flowing into the brush 40 bath 4 through the outlet 3. The brush bath is provided with drip flanges 6 which surround it and are inclined inward against which the brush can be wiped to remove surplus liquid which by this construction 45 flows back into the brush bath 4. A screwed cap 7 permanently attached to storage receptacle 1 by the chain 8 is provided to close the outlet 3 should only a portion of the stored liquid be used at one application when the 50 brush bath can be detached and dipped in cleansing liquid to remove any film or solidified matter which may have formed on it.

The liquid in the brush bath 4 is automatically replenished from the storage re-

ceptacle 1, as, when the level of the liquid 55 in the brush bath is lowered to the level of the top of the aperture 3, sufficient air is admitted to the storage receptacle to permit of a further flow of liquid into the brush bath.

A handle 10 can be provided on top of 60 the storage receptacle 1 for convenience and portability.

I claim as my invention:

1. A receptacle for varnish, paint, and the like, comprising a storage receptacle having 65 an exit and an inclined bottom leading to said exit, a brush bath detachably connected with said outlet and provided with internal drip flanges and a screw cap for closing said exit permanently attached to said receptacle. 70

2. A receptacle for liquid comprising a storage chamber having an inlet at its upper end, an outlet at its lower end, an inclined bottom which slopes from one side of the chamber toward the opposite side of the 75 same which has said outlet, and a brush bath having its lower end connected with the outlet of said chamber while its upper end is open and provided with an internal drip flange. 80

3. A receptacle for liquid comprising a storage chamber having an inlet at its upper end, an outlet at its lower end, an inclined bottom which slopes from one side of the chamber toward the opposite side of the 85 same which has said outlet, a brush bath detachably connected at its lower end with the outlet of said chamber and provided at its upper open end with an internal drip flange, and means for closing the outlet of 90 said chamber. 80

4. A receptacle for varnish and the like, comprising a storage receptacle having an outlet at its bottom and an inlet at its top, a closure for said inlet, a brush bath detachably connected with said outlet and having internal drip flanges, and a detachable closure for said outlet. 95

5. A receptacle for varnish and the like, comprising a storage receptacle having an 100 outlet at its bottom and an inlet at its top, a closure for said inlet, a brush bath detachably connected with said outlet and having internal drip flanges, and a detachable closure for said outlet, said receptacle having an inclined bottom which directs the contents of the receptacle to said outlet. 105

FRANK WHEELER PLANE.
